UNITED STATES PATENT OFFICE.

ALBERT GÉNAULT, OF COURBEVOIE, FRANCE.

FUEL-HEATER.

1,345,762.

Specification of Letters Patent.

Patented July 6, 1920.

Application filed September 19, 1918. Serial No. 254,852.

To all whom it may concern:

Be it known that I, ALBERT GÉNAULT, a citizen of the French Republic, residing at Courbevoie, Seine, France, 48 Rue Victor Hugo, have invented certain new and useful Improvements in Fuel-Heaters, of which the following is a specification.

This invention consists in improvements in carbureters for internal combustion engines, mainly for using heavy hydrocarbons such as petroleum &c.

The improvements consist more particularly in a peculiar diffusion apparatus for effecting a perfect atomization or mixture of the hydrocarbon with the air in such a manner as to produce a completely homogeneous and explosive mixture.

The improvements forming the subject matter of the invention consist essentially in causing air charged with hydrocarbon supplied from any suitable kind of carbureter, to pass alternately through a plurality of series of passages of small diameter that have been suitably designed as a function 25 of the requisite velocities of the mixture for producing atomization, and through expansion chambers.

The accompanying drawing illustrates by way of example a constructional form of an apparatus embodying the improvements of this invention.

In principle the improved apparatus consists of a carbureter casing 1 and its sprayer 2 of the usual type which projects partially 35 within the outlet branch 2' of the carbureter and above which are arranged blocks 3 and 4, the adjacent edges of which are nested together as at 3' while the lower portion of the upper block is recessed to provide an ex- 40 pansion chamber 5.

These blocks are pierced with passages 6 and 6^a of small diameter and are inclosed by a heating chamber 7 provided with two branches 8, 9. The lower portion of the 45 chamber 7 is threaded and removably engaged with the adjacent portion of the branch 2' and is formed with a seat for accommodating the projecting flange portion at the lower edge of the lower block 4. A flanged sleeve 9' is arranged about the upper portion and rests on the flanged portion of the block 3, while a union 10' is engaged with the sleeve and the upper portion of the 50 chamber 7 for releasably clamping the parts together in a compact and substantially rigid manner. A valve 11, arranged in the

casing of the apparatus, allows of regulating the admission of the mixture to the engine.

Operation: The hydrocarbon and air 60 drawn from the carbureter 1 and sprayer 2, in the condition of a non-homogeneous mixture, by the action of the depression produced by the suction of the engine piston, enter the passages 6 in the block 4. The 65 high velocities, the molecular friction and the contraction to which they are thereby subjected, effect their atomization by an intimate mixing of the hydrocarbon and air.

The mixture then passes into the expansion chamber 5 whence it passes farther through a series of passages 6^a of still smaller diameter in the block 3 for rendering the atomization still more complete. The mixture then passes to the engine by way 75 of the branch 2'.

In order to facilitate the carburation and avoid condensation of the hydrocarbon, the passages 6, 6^a are heated, either by means of a hot water circulation, or preferably by 80 means of the exhaust gases of the engine.

For this purpose the blocks 3 and 4 are inclosed in a heating chamber 7 provided with branches 8, 9 for the entrance and exit of the heating fluid whereby the passaged blocks 3, 4 are heated to a suitable temperature. Their mass and the small diameter of the passages cause these blocks to act to a certain extent as heat-accumulators, thereby avoiding sudden changes in the heating 90 temperature. The small diameter of the passages assures an intimate contact between the mixture to be heated and the hot surfaces of the passages.

The illustrated apparatus is given solely 95 by way of example. The number of the blocks and of the intermediate expansion chambers may be increased without departing from the essential nature of the invention.

Having now particularly described and ascertained the nature of my said invention and in what manner the same is to be performed I declare that what I claim is:—

1. The combination with the outlet branch 105 of a carbureter, of a pair of superposed and partially nested blocks interposed in the branch and provided with longitudinal passages, the passages in the upper block being smaller than the passages in the lower 110 block, one of the blocks being recessed at the adjacent edges of the blocks to provide an

expansion chamber, and a heating chamber arranged in spaced relation to and surrounding the blocks, the outer surface of the blocks forming one of the walls of the heating chamber.

2. The combination with the outlet branch of a carbureter, of a pair of superposed and partially nested blocks interposed in the branch and provided with longitudinal passages, the lower portion of the upper block being recessed to form an expansion chamber, flanges at the outer edges of the blocks, a heating chamber surrounding the blocks in spaced relation and having its lower portion removably connected to the branch and provided with a seat for accommodating the lowermost flange, a flanged sleeve surrounding the upper part of the branch and resting on the upper flange of the upper block, and 20 a union embracing the flanged sleeve and detachably engaged with the upper part of the heating chamber for removably clamping the parts in a substantially rigid compact position.

3. The combination with a carbureter 25 having an outlet branch, of a heater casing detachably connected to the outlet branch and provided with an inlet and an outlet, a pair of superposed and partially nested blocks located in the heater casing and each provided with a series of integral walls dividing the blocks into a series of longitudinal passages, one of the blocks being recessed at the adjacent ends of the blocks to provide an expansion chamber, the outer surfaces of the blocks being spaced away from the wall of the heater casing to provide a heating chamber having the outer surface of the blocks as its inner wall, a second outlet branch bearing 30 against the upper block, and means detachably connecting the second branch and heater casing and holding said blocks in fixed position within the heater casing.

Dated this 7th day of August, 1918. 45
In testimony whereof I affix my signature.

ALBERT GÉNAULT.
